OTHER PUBLICATIONS

U.S. Appl. No. 29/448,484, Corbin et al., "Battery Module", filed Mar. 12, 2013 (Not Published).

Primary Examiner — Rosemary K Tarcza(74) *Attorney, Agent, or Firm* — Sterne, Kessler, Goldstein & Fox P.L.L.C.(57) **CLAIM**

The ornamental design for a battery, as shown and described.

DESCRIPTION

FIG. 1 is a front view of a battery showing our new design; FIG. 2 is a rear view thereof;

FIG. 3 is a top plan view thereof;

FIG. 4 is a bottom view thereof;

FIG. 5 is a left side view thereof; and,

FIG. 6 is a right side view thereof.

The broken lines in the Figures show portions of the battery that form no part of the claimed design.

1 Claim, 4 Drawing Sheets(56)
